[57] CLAIM

The ornamental design for a combined door and wall sealer for a greenhouse frame, as shown and described.

DESCRIPTION

FIG. 1 is a top plan view of a combined door and wall sealer for a greenhouse frame showing my new design, the broken lines being disclosed for illustrative purposes only.

FIG. 2 is a side perspective view of my design for a combined door and wall sealer for a greenhouse frame;
FIG. 3 is a front elevation of my design;
FIG. 4 is a back elevation of my design;
FIG. 5 is a sectional view of my design shown in FIG. 2, taken along lines 5—5.
